DISPLAY STAND

Charles E. Pringle and Marie M. Murray, Milwaukee, Wis., assignors to Milwaukee Lace Paper Co., Milwaukee, Wis., a corporation of Wisconsin

Application November 4, 1940, Serial No. 364,156

5 Claims. (Cl. 211—135)

This invention relates to display stands, particularly to a collapsible display stand for shelf paper and the like.

Shelf paper is ordinarily made in strip form having a marginal portion of ornamental design extending along one edge thereof. It is ordinarily sold in predetermined lengths folded in a manner to expose to view a portion of the ornamental margin.

An object of the present invention is to provide a display rack for receiving and supporting a number of specimens of the folded shelf paper in superposed overlapping relation with the ornamental marginal portions thereof visible to the customer.

Another object is to provide such a display rack adjustable to accommodate and properly position shelf paper specimens of different widths.

Another object is to provide such a display rack which can be sent to a dealer in collapsed form, and by him easily and quickly assembled.

Other objects and advantages will appear from the following description of a display stand embodying the present invention.

In the accompanying drawing:

Figure 1 is a perspective view of an assembled display stand embodying the present invention.

Fig. 2 is a longitudinal sectional view of the stand of Fig. 1, showing the manner in which the specimens of shelf paper are ordinarily positioned thereby.

Fig. 3 is a perspective view of the adjustable gauge member employed for properly positioning the shelf paper specimens.

The display stand shown in the drawing comprises an outer frame member 11 of relatively stiff inexpensive sheet material such as card board or the like, bent to form substantially parallel side sections 13 and 14 and an intermediate end section 12. A series of shelf members 15 of like sheet material span the space between the side portions 13 and 14, and have protruding end tabs 16 which engage in horizontal slots 17 formed in the side members to support the shelves. It will be noted that the shelves are arranged in stepped receding relation one above another, so that the front portion of each is exposed from above.

The display stand shown also includes a gauge member 18 positioned at the rear of the shelves 15 to serve as an abutment for shelf paper specimens *a* to properly position the same for display purposes. It will be noted that the member 18 may occupy either of two positions, one position directly adjacent the shelves 15, and a second

position farther to the rear adjacent the back member 12 of the frame. It may thus accommodate shelf paper of two different widths and properly position either for display purposes.

5 It will be noted that with the rear member 18 in position, shelf paper specimens *a* may be inserted onto the shelves 15 against the member 18 as an abutment, and that when so placed they are automatically positioned in stepped relation, 10 so that the decorative marginal portion *a'* of each is exposed from above, for the inspection of a customer.

The adjustable gauge member 18 is supported by tabs 19 releasably engaged in inclined slots 20 or 21 formed in the side members 13 and 14. It will be noted that the tabs 19 are positioned at the sides of the gauge member 18 nearer one end thereof than the other, so that the effective height of the member 18 may be changed by reversing it top for bottom. In this way member 18, when positioned in the forward slots 20 adjacent the shelves, may be made to extend above the top shelf 15 to provide an abutment at the rear of such shelf. On the other hand, when positioned in the rear slots 21, the member 18 is preferably inverted and in such inverted position does not extend above the top shelf 15, so that the shelf paper on the top shelf may use the rear panel 12 itself as an abutment, hiding the member 18 from view.

25 All of the slots 17, 20 and 21 are made of notched form, with the gap at the apexes narrower than the thickness of the tab to be inserted. By this means the apexes between the 30 notches are sprung slightly upon insertion of the tab, giving a resilient gripping engagement.

35 For shipping purposes, the disassembled stand may be packed flat with the rear section 12 of the frame member and one of the side sections 40 13 or 14 disposed in one plane and the other side member folded down thereagainst.

45 Assembly is readily accomplished merely by positioning the frame member, and inserting the tabs of the shelf and gauge members in the slots, in which position they will firmly brace and support the frame member, the resilient grip of the notched slots serving to firmly hold the members in assembled relation.

50 Various changes may be made in the embodiment of the invention hereinabove specifically described without departing from or sacrificing the advantages of the invention as defined in the appended claims.

We claim:

55 1. A rack for displaying shelf paper and the

like comprising a pair of substantially parallel upright side members, a vertical series of shelves supported by and between said side members, said shelves being disposed in upwardly receding stepped relation with their forward edges exposed, a gauge member disposed rearwardly of said shelves to position display material thereon, and means for mounting said gauge member at various distances from said shelves, and at an angle equal to the angle of recession of said shelves.

2. In a display stand the combination of a series of horizontal shelves placed one above the other with the front edges thereof arranged in receding ascension and unobstructed to permit access to said shelves, side members supporting said shelves, a rear member, means on said side members for mounting said rear member adjacent the rear of said shelves at an inclination corresponding to the angle of recession thereof to thereby form an abutment at the rear of said shelves for positioning articles thereon, and means on said side members for mounting said rear member in a position parallel to said first named position but spaced therefrom longitudinally of said shelves to thereby form an abutment in a different longitudinal position with respect to said shelves.

3. In a display stand the combination of a series of horizontal shelves placed one above the other with the front edges thereof arranged in receding ascension and open to permit access to said shelves, side members supporting said shelves, a rear member, means on said side members for mounting said rear member adjacent the rear of said shelves at an inclination corresponding to the angle of recession thereof to thereby form an abutment at the rear of said shelves for positioning articles thereon, and means on said side members for mounting said rear member in a position parallel to said first named position but spaced therefrom longitudinally of said

shelves to thereby form an abutment in a different longitudinal position with respect to said shelves, the mounting means for said member being formed to permit positioning of said member with its top above the level of the uppermost shelf when in one mounted position and with the top of said member below the level of said uppermost shelf when in the second of said mounting positions.

10 4. A display stand comprising a frame having back and two side members, a series of horizontal shelves mounted one above the other between the sides of said frame with their front ends in receding ascension and open to permit access to said shelves, an abutment member having mounting tabs at the sides thereof, notches in said side members for receiving said tabs to thereby mount said abutment member at the rear of said shelves and at an inclination corresponding to the angle of recession of said shelves, said tabs being placed on the sides of said abutment member at a point offset from the center thereof to thereby position said member at different heights when said member is reversed top for bottom.

5. A display stand comprising a cardboard member having a portion forming a back and having side portions folded with respect thereto to form a U-shaped frame, a series of shelf members having mounting tabs at the sides thereof, a series of notches in said side members adapted to receive said tabs to thereby mount said shelves one above another in horizontal position with the front edges thereof in receding ascension, said notches being fluted and having a width at their narrowest point less than the thickness of said tabs to thereby grip said tabs, said shelf members being positioned and engaged with said frame to form a series of braces locking said stand 40 in erected position.

CHARLES E. PRINGLE,
MARIE M. MURRAY.
